ATTORNEY

UNITED STATES PATENT OFFICE.

HOWARD G. HUNN, OF CHICAGO, ILLINOIS.

CHAIR-IRON.

1,277,726.

Specification of Letters Patent. Patented Sept. 3, 1918.

Application filed April 16, 1918. Serial No. 228,821.

To all whom it may concern:

Be it known that I, HOWARD G. HUNN, a citizen of the United States, residing at Chicago, in the county of Cook and State of Illinois, have invented certain new and useful Improvements in Chair-Irons, of which the following is a specification.

My invention relates to improvements in chair irons, particularly applicable to 10 stenographers' chairs of the general type disclosed in United States Letters Patent Number 1,044,530, issued to me November 19, 1912.

The present invention is concerned with 15 the means for controlling the vertical and angular adjustment of the chair back, and its principal object is to provide effective and simplified means for firmly retaining the back in adjusted position.

20 Stated in general terms, the invention comprises mechanism in the nature of a wedge, or a plurality of wedges, for locking the chair back in vertically and angularly adjusted position.

25 The preferred embodiment of the invention is illustrated in the accompanying drawing, wherein—

Figure 1 is a side elevational view of a fragment of a chair to which my invention 30 is applied;

Fig. 2 is a top plan view, with the seat omitted, the back supporting standard appearing in section, and a portion of the main wedge block being broken away;

35 Fig. 3 is a perspective view of the main wedge block and one of the wedging jaws in coöperative position; and

Fig. 4 is a broken sectional view on the line 4—4 of Fig. 2.

40 In the drawing, 10 denotes the spindle or rod to which the arms 11 are attached which support the chair seat 12. The back rest is designated 13 and is secured to the back-rest-support or standard 14. It is of 45 practical advantage to have the rest 13 rigidly attached to its support 14, and to effect adjustment of the rest 13, both vertically and angularly, by movement of the support 14 and my invention is adapted to accomplish this purpose.

Supported from and extending rearwardly of the spindle 10 is a pair of oppositely disposed bracket arms 15, which con-

verge and are turned upwardly at their rear ends. Near such rear ends the arms 15 are 55 provided with aligned openings to receive a pintle 16 which serves to hold the main wedge block denoted generally by the numeral 17 between the arms 15. The wedge block 17 near its forward end is provided 60 with a transverse opening through a hub 18 into which the pintle 16 passes with a loose friction fit. The sides of the wedge block 17 are taperingly cored out as at 19 to accommodate the rear ends of the arms 65 15, which are shaped to snugly enter the cavities 19, and thus hold the block 17 rigidly on the pintle 16.

The rear end of the block 17 is provided 70 with the similar fluted or toothed wedge faces 20 and 21, each curved in the arc of a circle, and oppositely inclined at an angle from the approximately middle dividing line 22.

Pivottally supported on the pintle 16 is a 75 frame which comprises the side arms 23 and 24, a cross piece 25, and the flanges 26 turned at a right angle to the arms 23 and 24. The arms 23 and 24 are parallel to and outside of the arms 15, and the flanges 26 overlie the 80 inner or rear ends of the arms 15.

The side arms 23 and 24 of the frame are provided near their rear ends with aligned 85 openings to receive hubs on wedge jaws through which a threaded spindle 27 passes, and at one end the spindle is smooth and has a hand wheel 28 attached thereto by means of the pin 29. The spindle 27 may be rotated in either direction through the agency of the wheel 28.

90 Loosely mounted on the threaded portion of the spindle 27 is a pair of wedge jaws 30, each of which is substantially T-shaped, as clearly shown in Fig. 2. The spindle passes through the jaws 30 at a point in the stem adjacent the head of the jaw, and the opening in the jaw through which the spindle passes is screw threaded in correspondence with the threads of the spindle 27. Secured to the outer face of each jaw 30 in alignment 95 with the opening therethrough, is an annular hub 31 which bears in the openings in the side arms 23 and 24, and which hubs are also internally threaded to be engaged by the threads on the spindle 27. The outer 100 face 32 of the head of each jaw 30 is beveled,

for a purpose to be presently described, and the base 33 of the stem of each jaw is toothed and curved in the arc of a circle to conform to the configuration of the rear end of the 5 wedge block 17. One of the jaws 30, for example that shown at the upper portion in Fig. 2 is capable of moving along the spindle for practically its entire threaded length, while the range of movement of the other 10 jaw along the spindle is very small, being limited by a cross pin 34 extending through the spindle adjacent the inner face of this latter jaw.

As will be noted from Fig. 2, one face of 15 the standard 14 is arched, so that its two inclined sides 14^a are adapted to be engaged by the beveled faces 32 of the jaws 30, while the other face of the standard is provided with the oppositely disposed undercut 20 grooves 14^b into which the rear hooked ends 23^a and 24^a of the arms 23 and 24 are adapted to engage.

The operation of the device is as follows:—With the parts assembled as shown 25 in Fig. 2, the hand wheel 28 is turned in one direction, say toward the right, forcing the wedge jaws 30 toward each other and causing them to ride up on the inclined curved faces 20 of the wedge block 17. The movement of the wedge jaws toward each other 30 causes their beveled faces 32 to wedge against the arched sides 14^a of the standard 14, thus clamping the latter firmly in position. The toothed faces 33 of the jaws 30 interlock 35 with the toothed faces 20 of the wedge block and the parts are all thus rigidly interlocked. If it be desired to effect adjustment of the back rest 13 in a vertical direction only, the hand wheel 28 is turned to the left just a 40 sufficient distance to allow of the standard 14 being moved up and down, and when this vertical adjustment is made, the hand wheel is again turned toward the right and the standard clamped in adjusted position. If 45 backward or forward adjustment of the rest 13 is desired, say to the position indicated in dotted lines in Fig. 1, the hand wheel 28 is rotated toward the left sufficiently to permit of the toothed faces 33 of the wedge jaws 30 50 riding freely over the toothed faces 20 of the block 17. The frame 23—25 is then moved in the arc of a circle until the rest 13 is in the desired position of adjustment, and the hand wheel 28 thereupon again turned to the 55 right until the parts are firmly interlocked.

From the foregoing description of the construction and operation of the device it will be noted that both vertical and angular adjustment of the standard 14 is controlled 60 from the hand wheel 28, thus making it necessary to manipulate only one rotary member in adjusting the chair back, thereby conducing to simplicity and ease of handling.

I desire it to be understood that the 65 details of my invention are susceptible of con-

siderable modification, without departing from the spirit and scope of the invention as defined by the appended claims.

I claim:—

1. A chair iron, comprising a wedge block 70 having wedge faces receding from the middle line of said block, wedge jaws adapted to engage said wedge faces, a standard engageable by a part of said jaws, and means for controlling relative movement between 75 the block and the jaws.

2. A chair iron, comprising a wedge block having wedge faces receding from the middle line of said block, wedge jaws having 80 portions capable of engaging with the wedge faces of said block and additional portions coöperable with a standard, a standard adapted to be engaged by the last named portions of said jaws, and means for controlling relative movement between the block 85 and the jaws.

3. A chair iron, comprising a relatively fixed wedge block having wedge faces receding from the middle line of said block, wedge jaws movable in relation to said block 90 and engageable with the wedge faces thereof, a standard engageable by a part of said jaws and means for controlling the movement of said jaws in relation to said block.

4. A chair iron, comprising a wedge block, 95 wedge jaws coöperable therewith, means for effecting relative movement in the arc of a circle between said jaws and said block, means for effecting reciprocal movement of said jaws, and a standard engageable by a 100 part of said jaws.

5. A chair iron, comprising a relatively fixed wedge block, pivotally mounted wedge jaws movable in the arc of a circle in relation to said block, means for moving said 105 jaws toward and from each other, and a standard engageable by part of said jaws.

6. A chair iron, comprising a wedge block having a toothed face, wedge jaws having toothed portions coöperable with the toothed 110 face of said block, a standard engageable by a portion of said jaws, and means for controlling relative movement between said jaws and said block.

7. A chair iron, comprising a wedge block, 115 wedge jaws coöperable therewith and having beveled faces, a standard having an arched portion engageable by the beveled faces of said wedge jaws, and means for controlling relative movement between the block and the 120 jaws.

8. A chair iron, comprising a wedge block having a toothed face, wedge jaws having toothed faces coöperable with the toothed face of said block, said jaws also having 125 beveled faces, a standard having inclined faces engageable by the beveled faces of said jaws, and means for moving said jaws toward and from each other.

9. A chair iron, comprising a wedge block, 130

a frame pivoted thereto, wedge jaws carried by said frame and having portions coöperable with said wedge block and additional portions shaped to engage a standard, a standard engageable by the last named portions of said jaws, and means for controlling the movement of said jaws.

10. A chair iron, comprising a block having a toothed wedge face curved in the arc 10 of a circle, wedge jaws having toothed faces curved in the arc of a circle and coöperable with the wedge face of the block, beveled heads carried by said jaws, a standard having inclined faces coöperable with the beveled heads of said jaws, and means for controlling the movement of said jaws.

11. In a chair iron, the combination with a frame comprising arms having hooked ends, of a wedge block between the arms of said 20 frame, wedge jaws coöperable with said block and having beveled portions, a standard having inclined faces engageable by said

beveled portions and also having parts engageable by the hooked ends of said arms, and means for controlling the movement of 25 said wedge jaws.

12. In a chair iron, the combination with a frame comprising arms having hooked rear ends, of a wedge block between the arms of said frame, a pivot in said wedge block about 30 which said frame is adapted to rock, a pair of wedge jaws reciprocable toward and from each other in said frame, said jaws having beveled heads, a standard having an inclined front face engageable by the beveled heads 35 of the jaws and undercut grooves in its rear face engageable by the hooked ends of said arms, and means whereby said block, jaws and standard may be locked together or freed from one another. 40

In testimony whereof I have affixed my signature.

HOWARD G. HUNN.
